CORE RECOVERING TOOL

Alfred C. Catland, Alhambra, and John H. Howard, Huntington Park, Calif.; said Catland assignor to Globe Oil Tools Company, Los Nietos, Calif., a corporation of California

Application June 21, 1935, Serial No. 27,704

16 Claims. (Cl. 255—72)

This invention relates to a well tool and relates more particularly to a well tool for obtaining a core or sample of the earth formation. A general object of this invention is to provide a practical, dependable and particularly effective tool for obtaining a sample or core of the earth formation in a well bore.

Much difficulty has been encountered in providing a sample taking well drill or well core drill that is capable of obtaining and recovering a full sized unmutilated core. In many of the core drills recently developed the inner core receiving barrel is rotatably supported so that it may turn or be non-rotatable at will during the rotary drilling or coring operation to have less tendency to wear away and destroy the core. The rotatable mountings of the inner barrels of such tools have materially complicated the general construction of the tools and have necessitated the diverting of the circulation fluid past the rotatable mountings through ports of small diameter and of substantial length. The mud-laden circulation fluid passing through these ports under pressure quickly erodes and wears away the ported parts. Core drills usually embody core catchers and one of the most popular types of core catchers includes a ring-like body having depending springs carrying gripping slips which are actuated into gripping and holding engagement with the core through cooperation with an inclined surface on the interior of the tool. It has been found that the slips carried by the depending springs work downwardly on the inclined surface when the tool is being run into the well and are thus in their fully actuated positions before the actual coring operation is begun. As the core enters the tool its upper end encounters the actuated slips and the core is often destroyed by the slips as the drilling progresses. In other instances, the entering core engaging the slips causes the springs carrying the slips to be bent back upon themselves and broken resulting in the loss of the slips and mutilation and possible loss of the core.

Another object of this invention is to provide a core drill embodying a rotatably supported inner barrel and in which the parts are subject to a minimum of erosion by the circulation fluid and that is operable to obtain a core without the loss or destruction of the core engaging parts and with a minimum of mutilation of the core.

Another object of the invention is to provide a core drill that embodies a simple, effective means for rotatably supporting the lower end of the inner barrel in the bit head.

55 Another object of the invention is to provide a

core drill of the character mentioned that embodies an improved and simplified means for handling the circulation fluid.

Another object of the invention is to provide a core catcher that does not interfere with the entrance or passage of the core into the tool and that is capable of dependably recovering and retaining the core with a minimum of mutilation of the core.

Another object of this invention is to provide a core catcher comprising a body and slips located above the body and connected therewith by flexible springs or flexible members to be movable inwardly into gripping contact with the core by co-operation with an inclined face of the core drill. The slips of the improved core catcher of this invention, being above the core catcher body, as distinguished from the slips of the usual core catchers which are below the body, are less liable to mutilate the core as it enters the drill and the engagement of the slips with the entering core does not subject the flexible members to distorting or fracturing strains but merely puts them under tension.

Another object of the invention is to provide a core catcher embodying the novel combination of pivoted core-retaining dogs on the core catching body and core gripping slips above the body connected therewith by springs or flexible members. The spring urged pivoted dogs on the body are engaged by the core as it enters the drill and this engagement usually moves the core catcher to its inoperative position where the slips are retracted and cannot interfere with the core. In instances where the core passes through the series of dogs and the slips remain in their actuated positions the core engaging the slips readily moves them to their retracted positions without being mutilated and without injuring the core catcher.

Another object of this invention is to provide a core drill of the character mentioned embodying a bearing member on the lower end of the inner barrel for supporting it for rotation and a core catcher rotatably disposed in the bearing member whereby it may turn or remain stationary with respect to the inner barrel at will during the coring operation.

The various objects and features of our invention will be fully understood from the following detailed description of typical preferred forms and applications of the invention, throughout which description reference is made to the accompanying drawings, in which:

Fig. 1 is a side elevation of a drill embodying the present invention illustrating the lower major

portion in central vertical cross section. Fig. 2 is an enlarged transverse detailed sectional view taken substantially as indicated by line 2—2 on Fig. 3. Fig. 3 is an enlarged vertical detailed sectional view of the core catcher, the bearing member and the adjacent parts. Fig. 4 is an enlarged side elevation of the core catcher removed from the drill with a portion broken away to appear in vertical cross section. Fig. 5 is a transverse detailed sectional view of the core catcher taken substantially as indicated by line 5—5 on Fig. 4, and Fig. 6 is an enlarged fragmentary vertical sectional view of an alternative or modified construction.

15 The present invention as illustrated in Figs. 1 to 5, inclusive, of the drawings, includes, generally, an outer barrel 10 having a bit head 11 on its lower end, an inner barrel 12 rotatably supported in the bit head 11 and a core catcher 13. 20 The outer barrel 10 is an elongate tubular member adapted to be attached to the lower end of a well drilling string for operation in a well bore. A tubular connecting member or sub 14 is attached to the lower end of the outer barrel 10 25 to form an extension or part thereof. The sub 14 has a pin 15 on its lower end. A bit head sub 16 is threaded on the pin 15 and is provided with a socket 17 in its lower end. The bit head sub 16 constitutes a connecting member for connecting the bit head 11 with the lower part or sub 30 14 of the outer barrel 10.

35 The bit head 11 includes a tubular body or shoe 18. The shoe 18 has a pin 19 on its upper end threaded into the socket 17. The longitudinal opening 20 of the shoe 18 is adapted to receive a core. A socket 21 is provided in the pin portion or upper portion of the shoe 18 and has an upwardly facing annular shoulder 22 on its wall. The cutting head or bit head 11 has cutting means 40 for making an annular cut in the earth formation and for forming a core for reception in the tubular drill. In accordance with the broader aspects of the invention any type or character of cutting means may be embodied in the head 11. 45 In the particular embodiment of the invention disclosed in the drawings roller cutters 23 are rotatably supported in pockets or recesses 24 in the lower end of the shoe 18 and project from the lower end of the shoe to act on the formation at the bottom of the well bore. The cutters 23 are operable to make an annular cut in the earth formation as the drill is rotated and trim the core for proper reception in the shoe opening 20.

55 The inner barrel 12 is arranged longitudinally in the outer barrel 10 and is adapted to receive the core. The inner barrel 12 is preferably thin walled to be light in weight and is spaced from the interior of the outer barrel 10 leaving an annular fluid passage 25. The invention provides a novel and effective means for rotatably supporting the inner barrel 12 in the bit head 11. A tubular bearing member 26 is welded or otherwise secured to the lower end of the inner barrel 12 and extends downwardly through the bit head sub 16. The lower end of the bearing member 26 is received in the socket 21 of the shoe 18 and is adapted to rotatably bear on the shoulder 22 to rotatably support the inner barrel 12. The bearing member 26 extends longitudinally through the sub 16 with considerable clearance leaving an annular fluid passage 27. The upper end portion of the bearing member 26 preferably extends upwardly into the pin 15 to have rotatable bearing engagement with its internal wall. A hardened bushing 28 is provided on the bearing member 26 to bear upwardly against the

lower end of the pin 15 when the engagement of the core with the inner barrel 12 and its associated parts tends to hold the inner barrel against downward movement while the drill is being fed downwardly into the earth formation. Short ports 29 of substantial fluid capacity are provided in the bearing member 26 to connect the lower end of the annular passage 25 with the annular passage 27. In accordance with the invention the longitudinal opening 30 of the bearing member 26 has an enlarged or recessed portion with a downwardly and inwardly inclined wall or surface 31. A counter bore or socket 32 is provided in the lower end of the bearing member 26 to communicate with the opening in the shoe 18. The counter bore or socket 32 is preferably of substantially the same diameter as the communicating socket 21 of the shoe 18.

10 The core catcher 13 is an important feature of the present invention and is adapted to grip 20 and retain the core when the drill is raised and withdrawn from the well. The core catcher 13 includes a tubular or annular body 33. The body 33 of the core catcher is normally disposed in the socket 32 or the bearing member 26 and is movable into the shoe socket 21 when the core catcher is actuated. The core catcher body 33 has suitable clearance in the sockets 32 and 21 and its internal diameter is such that it readily receives and passes the core during the coring 30 operation. The body 33 is preferably formed of two telescopically assembled rings 34 and 35. The inner ring 34 projects downwardly beyond the lower end of the outer ring and the two rings are connected by spaced rivets 36. The upper end of 35 the core catcher body 33 is adapted to engage the upper wall of the socket 32 to limit the upward movement of the core catcher. The abutting surfaces of the rings 34 and 35 have annular grooves forming an annular opening 37. A plurality of circumferentially spaced recesses 38 are provided in the upper inner wall of the core catcher body 33 and intersect the annular opening 37.

45 The core catcher 13 includes a plurality of pivoted spring urged dogs 39 for assisting in breaking free the core and supporting the core. The dogs 39 are carried by the core catcher body 33 being pivotally mounted in the recesses 38. Pivot pins 40 extend through transverse openings in the 50 dogs 39 and have their opposite ends received in the annular opening 37 to support the dogs 39 for pivotal movement. The portions of the pivot pins 40 received in the opening 37 may be flattened to some extent so that their engagement with the 55 walls of the opening 37 hold the pins against turning and longitudinal movement. The dogs 39 pivotally supported, as just described, are movable or pivotable between projecting positions such as illustrated in the drawings where they 60 project inwardly to engage the core, and retracted positions where they are received in the recesses 38 to permit the free passage of the core through the core catcher. If desired or found practical the dogs 39 may be of different lengths, 65 as illustrated, to be effective in acting on hard full sized cores as well as softer cores of smaller diameter. The active ends of the dogs 39 are pointed or sharpened to effectively bite into the core. The dogs 39 have lower faces 41 which are 70 adapted to rest on or engage the lower walls of the recesses 38 to stop the downward pivoting of the dogs and support them in their core retaining positions. Notches 42 are provided in the outer or pivoted ends of the dogs 39. Springs 43 75

in the notches 42 surround the pivot pins 40 and react against the dogs 39 and the body 33 to yieldingly urge the dogs to their projected or actuated positions. Cam parts 44 may be provided on the outer ends of the dogs 39 to cooperate with a shoulder 45 on the interior of the shoe 18 to assist in pivoting the dogs to their fully projected positions when the core catcher is actuated.

In accordance with the invention the improved core catcher includes slips 46 located above the core catcher body 33 where they do not interfere with the free entrance of the core into the tool. The slips 46 are disposed in the longitudinal opening of the bearing member 26 and have inclined outer surfaces 47 for engaging the inclined surface 31 of the member. The inner sides of the slips 46 are provided with gripping teeth 48 for biting or gripping into the core. The slips 46 are circumferentially spaced and are normally or initially disposed at the upper portion of the inclined surface 31.

Spring members or flexible members 49 connect the gripping slips 46 with the core catcher body 33. The flexible members 49 may be attached to the core catcher body 33 by rivets or the like. In practice the members 49 may be attached to the body 33 by the above described rivets 36. The lower end portions of the spring members 49 are preferably counter sunk in the internal surface of the core catcher body. The spring members or flexible members 49 extend upwardly through the opening 30 and their upper portions may be normally inclined upwardly and outwardly to be substantially parallel with the surface 31. The flexible members 49 are attached to the outer or rear sides of the gripping slips 46 by rivets or the like. The members 49 are preferably recessed or counter sunk in the outer surfaces of the slips 46 so that they do not interfere with the engagement of the slips with the surface 31. The flexible members 49 may normally urge the slips 46 outwardly through their inherent resiliency to hold the slips in engagement with the inclined surface 31 and thus assist in preventing premature actuation of the slips.

In the drilling or coring operation circulation fluid is pumped downwardly through the drilling string and flows downwardly through the annular passage 25. The ports 29 conduct the fluid from the passage 25 to the passage 27. Spaced ports 50 are provided in the bit head shoe 18 and extend downwardly from the lower end of the passage 27 to the recesses 24 where they discharge the fluid against the cutters 23.

Fig. 6 of the drawings illustrates an alternative or modified form of construction. In the construction shown in Fig. 6 of the drawings the shoe 18a of the bit head has an internal thread 60 in the upper portion of its socket 21. The bit head sub 16a is threaded on the lower end of the sub 14 and has a pin 61 at its lower end provided with a thread for cooperating with the thread 60 of the bit head. The lower end of the pin 61 presents a downwardly facing annular shoulder 62. The interior of the lower portion or pin portion of the sub 16a has a downwardly and inwardly inclined surface 63 similar to the surface 31. An annular upwardly facing shoulder 64 occurs at the upper end of the surface 31 and a similar shoulder 65 is provided on the interior of the sub 16a above the shoulder 64.

It is a feature of the construction illustrated in Fig. 6 of the drawings that a sleeve 65 is welded or otherwise fixed to the shoulder 65 to extend

upwardly therefrom. The sleeve 65 is spaced from the interior of the sub 16a to leave an annular fluid passage 66. A bearing member 67 is welded to the lower end of the inner barrel 12 and its lower end may rotatably bear on the shoulder 64. A hardened bushing 68 may be provided on the bearing member 67 to engage the lower end of the sub 14 when the engagement of the inner barrel with the core tends to hold it against downward movement as the drill is fed into the formation. The core catcher 13 described above may be embodied in or employed in combination with the construction shown in Fig. 6 of the drawings. The core catcher 13 is arranged so that its body 33 is in the socket 21 of the shoe 18 below the shoulder 62. The gripping slips 46 are within the pin portion or lower portion of the sub 16a and are adapted to be actuated through cooperation with the inclined surface 63. The sleeve 65 is important as it provides the sub 16a with the annular fluid passage 66 which conducts the circulation fluid with a minimum of erosion to the sub. Short ports 70 are provided in the sub 16a to extend downwardly from the lower end of the passage 66 to communicate with an annular groove 71 in the upper end of the shoe 18a. Discharge ports 72 conduct the circulation fluid downwardly from the groove 71 to the cutting parts. Short ports 73 of comparatively large fluid capacity are provided in the bearing member 67 to conduct the circulation fluid downwardly from the annular passage 25 to the annular passage 66. It is believed that it will be apparent how the circulation fluid is conducted past or around the rotatable mounting 35 of the inner barrel 12 and the core catcher 13 without subjecting the parts to appreciable wear or erosion.

During operation of the core drill illustrated in Figs. 1 to 5, inclusive, of the drawings, the cutters 23 engage the formation at the bottom of the well bore and make an annular cut leaving a core which is received in the bit head opening 20 with suitable clearance. As the drilling progresses the core extends through the core catcher 13 and enters the inner barrel 12. When the upper end of the core enters the core catcher body 33 it is engaged by the pivoted dogs 39. The engagement of the dogs 39 with the upper end of the core usually causes the core catcher to move upwardly to its fully retracted position in the event the core catcher may have worked downwardly to a position where its slips 46 are actuated. In the event, however, the slips 46 have become prematurely actuated and are not freed by the engagement of the core with the dogs 39 the engagement of the upper end of the core with the actuated slips 46 readily shifts the slips to their retracted positions without injuring or breaking the flexible members 49. The engagement of the upper end of the core with the actuated slips 46 merely places the flexible members 49 under an upward strain or a tensile strain which they can sustain without danger of failure. Thus it will be seen that the slips 46 in being disposed above the core catcher body 33 are readily and automatically retracted when the drill enters the core catcher without subjecting any parts of the core catcher to breakage.

When a core of sufficient length has been drilled the drill is raised or moved upwardly to actuate the core catcher 13. Upward movement of the drill causes the sharpened pivoted dogs 39 to bite into the core which prevents or resists upward movement of the core catcher. The in-

clined surface 31 on the upwardly moving tool cooperates with the outer surfaces of the slips 46 to actuate the slips inwardly into tight gripping and holding engagement with the core. The engagement of the dogs 39 and the slips 46 with the core causes the core to be broken free from the formation. The dogs 39 and the slips 46 are adapted to dependably retain the core in the drill as the drill is withdrawn from the well bore.

Having described our typical preferred forms and applications of our invention we do not wish to be limited or restricted to the specific details herein set forth, but wish to reserve to ourselves any variations or modifications that may appear to those skilled in the art or fall within the scope of the following claims.

Having described our invention, we claim:

1. In a core drill having a tubular bit head for making an annular cut in the earth formation and an inner barrel for receiving the core, the combination of, a tubular bearing member secured to the lower end of the inner barrel rotatably bearing in the head to support the inner barrel, and a core catcher including a body rotatably arranged at the lower end of the member, and gripping members connected with the body and disposed in the member to be actuated against the core through cooperation with the member.

2. In a core drill having a tubular bit head for making an annular cut in the earth formation and an inner barrel for receiving the core, the combination of, a tubular bearing member secured to the lower end of the inner barrel rotatably bearing in the head to support the inner barrel, and a core catcher including a body rotatably arranged at the lower end of the member, flexible arms extending upwardly from the body into the member, and slips on the arms disposed in the member to be actuated against the core through cooperation with the interior of the member.

3. In a core drill having a tubular bit head for making an annular cut in the earth formation and an inner barrel for receiving the core, the combination of, a tubular bearing member secured to the lower end of the inner barrel rotatably bearing in the head to support the inner barrel, and a core catcher including a body rotatable in the member, core gripping dogs on the body, flexible arms on the body extending upwardly through the member, and core gripping slips on the arms disposed in the member to be actuated through cooperation with the interior thereof.

4. In a core drill construction, a tubular bit head for making an annular cut in the earth formation and thus leave a core, a tubular connecting member attached to and extending upwardly from the head to connect the head with an outer barrel, an inner barrel for receiving the core, and a bearing member on the lower end of the inner barrel rotatably bearing in the head to support the inner barrel, the bearing member extending through the connecting member with clearance to leave an annular passage therein for receiving the down flowing circulation fluid from the outer barrel, there being discharge ports in the head receiving the fluid from the passage.

5. In a core drill construction, a tubular bit head for making an annular cut in the earth formation and thus leave a core, a tubular connecting member attached to and extending upwardly from the head to connect the head with an outer barrel, an inner barrel for receiving the

core, and a bearing member on the lower end of the inner barrel, the bearing member extending through the connecting member with clearance to leave an annular passage therein for receiving the down flowing circulation fluid from the outer barrel, there being discharge ports in the head receiving the fluid from the passage, there being a counter bore in the lower end of the bearing member communicating with and forming a continuation of the central opening of the tubular head.

6. In a core drill construction having a head for making an annular cut in the earth formation and a tubular connecting member attached to and extending upwardly from the head to connect the head with an outer barrel, the combination of an inner barrel for receiving the core, a tubular bearing member attached to the lower end of the inner barrel for rotatably bearing in the head to support the inner barrel, the bearing member extending through the connecting member with clearance to leave an annular passage for receiving the down flowing circulation fluid from the outer barrel, and an inclined face on the interior of the bearing member for actuating core gripping slips.

7. In a core drill construction having an inner barrel for receiving the core, the combination of, a tubular bearing member secured to the lower end of the inner barrel for rotatably supporting the inner barrel, an inclined face on the interior of the bearing member, a core catcher body rotatable in the bearing member, flexible arms extending upwardly from the said body, and slips on the arms operable inwardly to grip the core through cooperation with said face.

8. In a core drill construction, a tubular bit head for making an annular cut in the earth formation, an outer barrel adapted to be connected to a drilling string, a tubular connecting member connecting the bit head with the outer barrel, an inner barrel extending through the outer barrel with clearance to leave an annular fluid passage and supported in the bit head, there being fluid discharge ports in the bit head, and a sleeve rigidly secured to the connecting member in spaced relation to its interior leaving an annular space which connects the annular fluid passage with the ports.

9. In a core drill having a barrel and bit head with fluid discharge ports therein, a tubular member for connecting the bit head with the lower end of the barrel, and a sleeve rigidly secured to the member in spaced relation to its internal wall leaving an annular passage communicating with the interior of the barrel, there being ports in the member connecting the lower end of the annular passage with the ports in the head.

10. A core catcher for use in a core drill having an inclined internal surface including a body adapted to be movably arranged in the drill below said surface, flexible members attached to the body and projecting upwardly therefrom, and core gripping slips on the flexible members actuated through cooperation with the said surface.

11. A core catcher for use in a core drill having an inclined internal surface including a body adapted to be movably arranged in the drill below said surface, a flexible member attached to the body and projecting upwardly therefrom, and a core gripping slip on the upper end of the flexible member operable inwardly to grip a core through cooperation with said surface on relative movement between the drill and body.

12. A core catcher for use in a core drill having an inclined internal surface including a body adapted to be arranged in the drill for relative

movement, means on the body for engaging a core to resist movement of the body relative to the core, a flexible member secured to the body and projecting upwardly therefrom, and a core gripping slip on the upper portion of the flexible member actuated inwardly to grip a core by cooperation with said surface on upward movement of the drill relative to the body.

13. A core catcher for use in a core drill having an inclined internal surface including a body adapted to be arranged in the drill for relative movement, spring urged parts on the body for engaging a core to resist movement of the body relative to the core, a flexible member secured to the body and projecting upwardly therefrom, and a core gripping slip on the upper portion of the flexible member actuated inwardly to grip a core by cooperation with said surface on upward movement of the drill relative to the body.

14. A core catcher for use in a core drill having an inclined internal surface including a body adapted to be arranged in the drill for relative movement, means on the body for engaging a core to resist movement of the body relative to the core, a flexible member secured to the body and projecting upwardly therefrom, and a core gripping slip on the upper portion of the flexible member urged against said surface by the resiliency of the member and actuated inwardly by said surface when the drill is moved vertically relative to the body.

15. A core catcher for use in a core drill having an inclined internal surface including a body adapted to be arranged in the drill below said surface for movement relative to the drill, core gripping dogs on the body adapted to engage the core to hold the body against movement when the drill is moved, flexible members secured to and projecting upwardly from the body, and slips on the members operable inwardly to grip a core by said surface on vertical movement of the drill relative to the body.

16. A core catcher for use in a core drill having an inclined internal surface including a body adapted to be arranged in the drill below said surface for vertical movement and rotation, core gripping dogs on the body, spring means urging the dogs inwardly against the core to resist movement of the body relative to the core, flexible members attached to the body and projecting upwardly therefrom, and slips on the flexible members operable inwardly by said surface to grip the core on relative movement between the drill and body.

ALFRED C. CATLAND.
JOHN H. HOWARD.
